UNITED STATES PATENT OFFICE.

PAUL H. WAGGENER, OF COLUMBIA, KENTUCKY.

ENVELOP.

Specification of Letters Patent. Patented Sept. 26, 1916.

1,199,131.

Application filed December 26, 1914. Serial No. 879,129.

To all whom it may concern:

Be it known that I, PAUL H. WAGGENER, a citizen of the United States, residing at Columbia, in the county of Adair and State 5 of Kentucky, have invented a new and useful Envelop, of which the following is a specification.

The present invention relates to improvements in envelopes, one object of the invention, being the provision of a novel construction of return envelop, in which the same may be maintained folded when sent outward and be readily released to be folded and maintained in such folded condition when 15 returned, there being novel means provided for forming a temporary connection upon the forwarding of the envelop which permits the same to be readily disengaged or severed to permit the opening and proper 20 folding and sealing of the return envelop.

A further object of the present invention, is the provision of an envelop of this character, which is readily folded in either position and which contains proper writing surface 25 faces for reports and bills, or order blanks, thus producing a thoroughly efficient and practical envelop of this character.

The invention is illustrated in the accompanying drawing, wherein:—

30 Figure 1 is a plan view of one of the envelopes in flat or blank form. Fig. 2 is a similar view of another form. Fig. 3 is a similar view of another variation.

Each of the envelopes is formed of a blank, 35 and embodies a body or central portion 1 having a final sealing flap 2 projecting therefrom and provided with mucilage or adhesive. The body portion 1 is provided illustrated in Fig. 1 has a temporary sealing 40 flap 3^m opposite the flap 2, and of tapered form, the flap 3^m being provided with a detachable or severable adhesive tab 4^m at its free end. The body portion 1 is provided with a pair of opposite side flaps 5^c, one of 45 which is provided at its free end with adhesive tabs 9. The flaps 5^c are adapted to overlap.

In use, the letter, statement, printed matter, or the like, can be provided upon the in-

ner surfaces of the body portion and flaps, 50 and also upon the outer surface of the body portion if desired. When the envelop is mailed the first time, the flap 2 is first folded upon the body portion 1, and the two side flaps 5^c are then folded upon the flap 2, and 55 finally, the flap 3^m is folded upon the flaps 5^c, the tab 4^m being moistened so as to adhere to the basal portion of the flap 2. The flaps 5^c will overlap one another and can be pasted together, or left free, in order that they can 60 be pasted together when the envelop is returned. The first address is written upon the flap 3^m which is outermost, and when the envelop is received, it is opened by severing the tab 4^m from the flap 3^m. Then, when the 65 envelop is returned, the flap 3^m is folded upon the body portion, and the flaps 5^c are then folded upon the flap 3^m and can be pasted together, and the flap 2 is finally 70 folder over the flaps 5^c and pasted to the flaps 3^m and 5^c. The tab 4^m can be made detachable by a score line between the flap 3^m and tab 4^m. The use of the flaps 5^c which can be pasted together, enables the envelop 75 to be mailed first class, or second class when the flaps 5^c are not attached, and which enables them to be pulled out for purpose of inspection.

In the form illustrated in Fig. 2, the temporary sealing flap 30 is of about the same 80 shape as the final sealing flap 2, and the adhesive tab 40 of the flap 30 is shorter than said flap. The side flaps 5^c are tapered, and one of them has the adhesive tab 12 at its free end to be pasted to the other side flap. 85

In the variation illustrated in Fig. 3, the adhesive tab 4^p is co-extensive in length with the flap 3^p, and the side flaps 5^c are of different form than those shown in Fig. 2, or practically the same as those shown in Fig. 90 1, with the exception that one of the flaps 5^c has a single elongated adhesive tab 13 at its free end instead of two tabs 9 as seen in Fig. 1.

What is claimed is:

An envelop embodying a central portion having a final sealing flap projecting therefrom and provided with adhesive, an oppo-

site temporary sealing flap provided with a detachable adhesive tab at its free end, and a pair of opposite side flaps, the free end of one side flap being provided with adhesive and being arranged to overlap and be secured to the other side flap.

In testimony that I claim the foregoing

Copies of this patent may be obtained for five cents each, by addressing the "Commissioner of Patents, Washington, D. C."

as my own, I have hereto affixed my signature in the presence of two witnesses.

PAUL H. WAGGENER.
